UNITED STATES PATENT OFFICE.

ANDREW E. ANDERSON, OF BROWNSVILLE, TEXAS.

TAPE-MEASURE.

1,248,435.

Specification of Letters Patent.

Patented Dec. 4, 1917.

Application filed March 18, 1917. Serial No. 154,451.

To all whom it may concern:

Be it known that I, ANDREW E. ANDERSON, a citizen of the United States of America, residing at Brownsville, in the county 5 of Cameron and State of Texas, have invented certain new and useful Improvements in Tape-Measures, of which the following is a specification.

My present invention relates to improvements 10 in tape measures, and is designed primarily for the purpose of providing an attachment for the end of the usual tape measure which will aid a person in making measurements alone; and in order to 15 accomplish this, it is a purpose of this invention to furnish a releasing device for the attaching claw or tooth when it is desired that the claw or tooth be released as well as furnish a protective shield for the point of 20 the claw or tooth of the attaching device, when it is not in use, or is being dragged over the ground or floor.

Another object of the invention is the 25 provision of a device of the character above indicated which is comparatively simple in construction, durable, inexpensive of production, and automatic in its operation, and the invention consists in certain novel 30 combinations and arrangements of parts as will be hereinafter more fully disclosed.

In the accompanying drawings I have 35 illustrated two forms of the invention which are physical embodiments of the best modes I have so far devised for the practical application of the principles of my invention, but it will be understood that I contemplate using other forms of springs, which may 40 be substituted for the flat springs utilized in the accompanying exemplifications of my invention, and other changes or alterations may be made and are contemplated, without departing from the spirit of my invention or the scope of my claims.

Referring to Figures 1 to 4 of the accompanying drawings: Fig. 1 is a top plan view 45 of the end of a tape line or tape measure having attached thereto the device of my invention.

Fig. 2 is an edge view of the device of 50 Fig. 1 showing the attaching claw in actual use as when measuring a lineal distance.

Fig. 3 is a longitudinal sectional view of 55 the device, in inoperative position, the spring acting as a shield or protection for the attaching claw.

Fig. 4 is an end view of the device as in Fig. 3.

In Figs. 5 and 6 a slightly modified form of the attaching claw is illustrated, as also is the attachment of the tape to the plate 60 somewhat altered. Fig. 5 is a sectional view of the modified form of the invention, and Fig. 6 is an end view of the device embodied in Fig. 5.

The attaching device of the first four figures of the drawing comprises a metallic plate 1 of suitable size and shape having a finger or thumb opening 2, and a slot 3 for the tape 4, the tape being provided with the usual graduations. At its forward or 70 outer end the plate is formed with a pair of hooks or claws 5, 5, preferably sharpened at 6 so that they may be embedded in wood or other similar material. In Fig. 2, however the claws are illustrated, as they would 75 be used by a carpenter, and are fastened over the corner C, which may be the end of a timber, the corner of a house, or other angular object.

An automatic, quick release device for 80 these claws is furnished by the flat spring 7 which is preferably fashioned with an upwardly bent end 8, and is attached or fixed to the plate 1 by having one end clamped around a portion of the body of the plate as 85 indicated at 9. The resilient or operative portion of the spring is located under the plate, and the bent end or flange 8 of the spring is guided between the walls of the open slot 10 formed at the end of the clamp 90 and between the two claws or hooks 5, 5.

The end of the tape line 4 may be attached to the spring as by a fixed ring or loop 11 which surrounds the spring, and then the end of the tape measure is looped 95 around this ring and stitched or sewed in the usual manner.

In the modified form of the invention as shown in Figs. 5 and 6, the tape measure is attached directly to the end of the plate 1^a, 100 the spring 7^a is attached to the plate as in the previous figures, but instead of using two claws or hooks, I utilize only one hook as 5^a and the bent end 8^a is adapted to move up into the corner of the plate and claw 105 when the device is in operative position.

In use both forms of the device are manipulated alike. When it is desired to measure the top surface of the object in Fig. 2 the claw or hook is first caught over the end 110

and the spring 7 is simultaneously pressed against the surface of the object preferably by the action of the thumb on the plate, and this pressure causes the device to assume the 5 position of Fig. 2, wherein the claw or hook is caught over the end of the object and the tape measure is held taut. With the line 10 taut the measurement is taken and noted, and then the line or tape is slackened, and 15 instantly the spring acts to lift the plate and free the claws of the corner C so that the tape may be wound as usual. Sometimes the device is used by pressing the points of the claws into soft wood or other material 20 and simultaneously tensioning the spring as before. In this case the line is also held taut for measurements, but when the tape is slackened the tension of the spring will lift the claws or prongs free of the material as 25 in the first instance. It will thus be seen that the tape may be used by one person, who first hooks the claws over the corner of the object and holds the tape taut while laying it upon the surface for measurement, 30 and when the measurement has been secured the claws are freed and the tape may be wound if desired from where the person is standing or has taken the measurement, the spring acting as a shield or protection for 35 the sharpened ends of the prongs as the device is dragged over the ground or surface.

As before stated other forms of springs, 35 may be used if desired for automatically releasing the claws, and the form of the claws may be varied to suit different conditions, i. e. a plumber for his work would require the services of a hook, a carpenter's work

would best be adapted for the claws illustrated, a quarryman would use a straight prong, and other tradesmen would need 40 specific forms of attaching members, but in each case the spring will automatically release the device.

What I claim is:

1. The combination with a tape measure 45 of an attaching device comprising a plate and a friction-holding member operative when the tape is taut, and means for releasing the attaching device when the tape is slackened. 50
2. The combination with a tape measure having an attaching device operative when the tape is taut, and a spring co-operating with said device to release it when the tape is slackened. 55
3. The combination with a tape measure having an attaching device comprising a friction holding member operative when the tape is held taut, and a compressed spring for releasing said device when the 60 tape is slackened.
4. The combination with a tape measure of a plate having an end claw adapted to frictionally engage an object and a spring fastened to the plate adapted to release said 65 claw.
5. The combination with a tape measure of a plate having an end claw adapted to frictionally engage an object, a spring fastened to the plate adapted to release the claw, 70 and said spring having a bent end for the purpose described.

In testimony whereof I affix my signature.

ANDREW E. ANDERSON.
